UNITED STATES PATENT OFFICE.

BERNT A. NELSON, OF MUSKEGON, MICHIGAN.

RAIL-DRILLING MACHINE.

1,246,144.

Specification of Letters Patent. Patented Nov. 13, 1917.

Application filed April 19, 1917. Serial No. 163,195.

To all whom it may concern:

Be it known that I, BERNT A. NELSON, a citizen of Sweden, residing at Muskegon, in the county of Muskegon and State of Michigan, U. S. A., have invented certain new and useful Improvements in Rail-Drilling Machines, of which the following is a specification.

This invention relates to improvements 10 in rail drilling machines.

The main objects of this invention are:

First, to provide an improved rail drilling machine which may be quickly adjusted to and from drilling position.

15 Second, to provide an improved rail drilling machine which is of light weight and easily adjusted to and removed from the track.

Third, to provide an improved rail drilling 20 machine which may be trundled or pushed along upon the track or upon the ground.

Fourth, to provide an improved rail drilling machine which is simple and economical 25 and of large capacity.

Further objects, and objects relating to structural details, will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated 35 in the accompanying drawing forming a part of this specification, in which:

Figure I is a front perspective view of my improved rail drilling machine with the parts in the position occupied when the 40 machine is trundled or pushed along on a track.

Fig. II is a detail plan view showing the machine adjusted to a track, the track being shown in conventional form.

45 Fig. III is an inverted detail view showing the arrangement of the drills, the drills being shown in the partially advanced position.

Fig. IV is an enlarged detail transverse 50 section on a line corresponding to line 4—4 of Fig. II.

Fig. V is a detail view partially in section on a line corresponding to line 5—5 of Fig. III.

55 Fig. VI is an enlarged detail partially in section on a line corresponding to line 6—6

of Fig. IV, showing details of the frame structure.

In the drawing, similar reference characters refer to similar parts throughout the 60 several views, and the sectional views are taken looking in the direction of the little arrows at the ends of the section lines.

Referring to the drawing, 1—1 represents the rails of a railway track. I pro- 65

vide a pair of flanged track wheels 2 adapted to travel on the rails or upon the ground as may be desired. These wheels are rotatably mounted upon the axle 3 to which the front ends of the longitudinal frame mem- 70

bers 4 are connected by means of the couplings 5. A transverse supporting bar 6 is secured to the longitudinal members 4 by means of the clips 7. This transverse bar is preferably formed of T-iron and is adapt- 75

ed to rest upon the rails when the machine is in drilling position. The rear ends of

the longitudinal frame members 4 are ex- 80

tended rearwardly and upwardly to pro- 85

vide handles 8 by means of which the ma- 90

chine may be handled in transporting it along the track or ground or in adjusting

it to and from the track.

The axle 3, the longitudinal frame mem- 95

bers 4 and the supporting bar 6 are con- 100

nected to provide a rigid frame. The sup- 105

porting bar 6 is provided with a rail hook

9 at one end, the hook being adapted to

engage over the rail as shown in Fig. IV.

On the under side of the supporting bar 6

I secure the drill frame 10 which is dis- 110

posed with its outer end 11 spaced from the

hook so as to receive the head of a rail be- 115

tween them, see Fig. IV.

The frame 10 is provided with hangers 12

through the front pair of which the drill

spindles 13 are disposed. These drill spin- 120

des are provided at their front ends with

chucks 14 for the drills 15 and at their rear

ends with pinions 16. The driving shaft 17

is mounted on the rear pair of hangers 12

between the spindles and is provided with

a pinion 18 of such length as to permit axial

movement of the spindles without carrying

the pinions out of mesh.

The feed bar 19 is perforated to receive

the spindles and on either side of this bar

I provide thrust collars 20 so that as the

bar is shifted the spindles are fed and re- 130

tracted. This bar is shifted by means of

the feed lever 21 which is bifurcated at its

lower end, its arms being pivoted at 22 to

the drill frame, the lower ends of the arms being connected by the links 23 to the ends of the feed bar.

The motor designated generally by the 5 numeral 24 is mounted on the axle and supporting bar 6, by means of the brackets 25 and 26 respectively. The motor is connected to the driving shaft 17 by the sprocket chain 27, the sprocket 28 on the motor shaft and 10 the sprocket 29 on the driving shaft. Various of the parts are shown more or less in conventional form as their structural details form no part of this invention.

With the parts thus arranged the machine 15 may be trundled along the track to the point of drilling and adjusted or engaged with the track merely by dropping the supporting bar 6 thereon with the hook 9 in engagement with the rail. By means 20 of the motor and the feed means described the drilling operations may be quickly performed and the machine is released as soon as the drills are retracted. The machine may be quickly removed from the track as 25 occasion may require. It is light in weight and if desired the operator may step between the axle and supporting bar and grasping these parts lift the machine to and from the rails, or it may be manipulated to and from the rails by means of the 30 handles 8.

I have illustrated and described my improvements in an embodiment which is simple and which I have found to be very practical. I have not attempted to illustrate or 35 describe various modifications and other adaptations which I contemplate as I believe the disclosure made will enable those skilled in the art to which my invention relates to 40 embody or adapt the same as may be desired.

Having thus described my invention, what I claim as new and desire to secure by Letters Patent is:

1. In a rail drilling machine, the combination 45 with a pair of track wheels, an axle on which said wheels are mounted, a pair of longitudinal members extended to provide handles by means of which the machine may be trundled, a support bar mounted on said 50 longitudinal members and adapted to rest upon the rails and provided with a rail hook at one end, said axle, longitudinal members and support bar constituting a rigid main frame, a drill frame mounted on the under 55 side of said support bar with its outer end in a spaced relation to said rail hook to receive a rail head between, drill spindles mounted for axial movement in said drill frame and provided with spindle pinions at their inner 60 ends, a driving shaft provided with a driving pinion meshing with said spindle pinions, said driving pinion being of such length as to permit axial movement of said spindle pinions, means for feeding said spindles, a 65 motor mounted on said main frame, and

driving connections from said motor to said driving shaft.

2. In a rail drilling machine, the combination with a pair of track wheels, an axle on which said wheels are mounted, a pair of longitudinal members extended to provide handles by means of which the machine may be trundled, a support bar mounted on said longitudinal members and adapted to rest upon the rails and provided with a rail hook at one end, said axle, longitudinal members and support bar constituting a rigid main frame, a drill frame mounted on said support bar, drill spindles mounted for axial movement in said drill frame and provided with spindle pinions at their inner ends, a driving shaft provided with a driving pinion meshing with said spindle pinions, said driving pinion being of such length as to permit axial movement of said spindle pinions, means for feeding said spindles, a motor mounted on said main frame, and driving connections from said motor to said driving shaft.

3. In a rail drilling machine, the combination with a pair of track wheels, an axle on which said wheels are mounted, a pair of longitudinal members extended to provide handles by means of which the machine may be trundled, a support bar mounted on said longitudinal members and adapted to rest upon the rails and provided with a rail hook at one end, said axle, longitudinal members and support bar constituting a rigid main frame, a drill frame mounted on said support bar, drill spindles mounted for axial movement in said drill frame and provided with spindle pinions at their inner ends, a driving shaft provided with a driving pinion meshing with said spindle pinions, said driving pinion being of such length as to permit axial movement of said spindle pinions, means for feeding said spindles, a motor mounted on said main frame, and driving connections from said motor to said driving shaft.

4. In a rail drilling machine the combination with a pair of track wheels, an axle on which said wheels are mounted, a pair of longitudinal members extended to provide handles by means of which the machine may be trundled, a support bar mounted on said longitudinal members and adapted to rest upon the rails and provided with a rail hook at one end, said axle, longitudinal members and support bar constituting a rigid main frame, a drill frame mounted on the under side of said support bar with its outer end in a spaced relation to said rail hook to receive a rail head between, a drill spindle mounted for axial movement in said drill frame, and a feed means for said spindle.

5. In a rail drilling machine, the combination with a pair of track wheels, an axle on which said wheels are mounted, a pair of longitudinal members extended to provide 5 handles by means of which the machine may be trundled, a support bar mounted on said longitudinal members and adapted to rest upon the rails and provided with a rail hook at one end, said axle, longitudinal members 10 and support bar constituting a rigid main frame, a drill frame mounted on said support bar, a drill spindle mounted for axial movement in said drill frame, and a feed means for said spindle.
- 15 6. In a rail drilling machine, the combination of a main frame comprising an axle, longitudinal members constituting handles, and a supporting bar adapted to rest upon the rails and provided with a rail engaging 20 hook, track wheels on said axle, a drill frame mounted on the under side of said supporting bar with its outer end in a spaced relation to its said rail hook to receive a rail head between, a drill spindle mounted on 25 said drill frame for axial movement and provided with a pinion, a driving shaft provided with a driving pinion meshing with said spindle pinion, said driving pinion being of such length as to permit axial movement of said drill spindle pinion as the spindle is fed and retracted, and a motor mounted on said main frame and having driving 30 connections to said driving shaft.
7. In a rail drilling machine, the combination of a main frame comprising an axle, longitudinal members constituting handles, and a supporting bar adapted to rest upon the rails and provided with a rail engaging hook, track wheels on said axle, a drill frame 35 mounted on said supporting bar, a drill spindle mounted on said drill frame for axial movement and provided with a driving pinion meshing with said spindle pinion, said driving pinion being of such length as to 40 permit axial movement of said drill spindle pinion as the spindle is fed and retracted, and a motor mounted on said main frame and having driving 45 connections to said driving shaft.
- 50 8. In a rail drilling machine, the combination of a main frame comprising an axle, longitudinal members constituting handles, and a supporting bar adapted to rest upon the rails and provided with a rail engaging hook, track wheels on said axle, a drill frame 55 mounted on said supporting bar, a drill spindle mounted on said drill frame for axial movement and provided with a pinion, a driving shaft provided with a driving pinion 60 meshing with said spindle pinion, said driving pinion being of such length as to permit axial movement of said drill spindle pinion as the spindle is fed and retracted, a feed bar operatively associated with said drill spindle, a feed lever, and a link connecting said 65 lever to said feed bar.
9. In a rail drilling machine, the combination of track wheels, a frame comprising a supporting bar adapted to rest on the rails and support one end of said frame during 70 drilling operations and provided with a rail hook, said frame being provided with a handle by means of which the supporting bar can be raised from the track and the machine may be trundled along a track, a drill 75 frame mounted on said supporting bar, a drill spindle mounted on said drill frame, and a feed lever for said drill spindle carried by said supporting bar.
10. In a rail drilling machine, the combination with track wheels, of a frame adapted to be trundled along a track on said wheels, a supporting bar adapted to rest on the rails and support one end of said frame during 80 drilling operations and provided with a rail hook, a drill spindle carried by said frame, and a motor mounted on said frame and having driving connections with said drill 85 spindle.
11. In a rail drilling machine, the combination with track wheels, of a frame adapted to be trundled along a track on said wheels, a supporting bar adapted to rest on the rails and support one end of said frame during 90 drilling operations and provided with a rail hook, and a drill spindle carried by said frame.
12. In a rail drilling machine, the combination with track wheels, of a frame adapted to be trundled along a track, a supporting 100 bar adapted to rest on the rails and support one end of said frame during drilling operations, a rail hook carried by said bar, and a drill spindle carried by said bar.
13. In a rail drilling machine, the combination with a frame, of wheels for supporting one end of said frame, a supporting bar for supporting the other end of said frame during drilling operations adapted to rest upon the rail to be drilled and anchor the 110 machine in drilling relation thereto and to be lifted from the track to permit the machine to be trundled along the track on said wheels, a drill spindle carried by said bar, and means for driving said drill spindle.
- 115 In witness whereof, I have hereunto set my hand and seal in the presence of two witnesses.
